RAILWAY TRACK CONSTRUCTION

Carl Weber, New York, N. Y., and Kenneth L. Henson, Rochelle Park, N. J., assignors, by mesne assignments, to Carl Weber, New York, N. Y.

Application September 21, 1954, Serial No. 457,406

4 Claims. (Cl. 238—2)

This invention relates to the construction of railway tracks. The invention is characterized by the provision of rail-supporting crosstie slabs, of precast concrete or equivalent imperishable material, which provide more effective support for the rails than is afforded by conventional wooden crossties, and which make for a more durable track requiring less maintenance than when conventional rock-ballasted wooden crossties are used.

The generally adopted methods of construction of railway tracks have not been changed in over one hundred years. They comprise the use of wood or comparable crossties for the support of the steel rails which are spiked thereto the correct gauge spacing apart. To reduce the rail pressure on the ties, steel plates are inserted under the rails. These steel plates also serve to equalize the lateral shearing stresses to the spikes.

The crossties rest on a crushed stone or gravel ballast bed. The track is stabilized in vertical position by compacting the ballast under the ties. These must be placed some distance apart from each other to permit the use of ballast tampers on both sides of every crosstie. Thus the supporting value of every crosstie is limited to its compacted surface area, and the rail between ties is subjected to bending stresses. Since the bearing value of the crosstie foundation cannot be increased, it has become necessary to adopt very heavy steel rails to meet the ever increasing demands for heavier and speedier train service.

One of the largest items of cost in railway operations is for the maintenance of the track. The perishable wooden crossties must frequently be replaced. Water from rain or melting snow penetrates the ballast bed, causing softening of the supporting soil with consequent subsidence of the track. These deficiencies must periodically be corrected to maintain safe traffic conditions.

Our new railway track construction eliminates the use of wooden crossties with their tie plates and spikes, and the disadvantages incident thereto. It also renders the use of stone or gravel ballast superfluous. In accordance with our invention, the railway track comprises a plurality of rail-supporting crosstie slabs, and rails supported on and secured to said slabs, said slabs having a length in the direction of the roadbed materially greater than the spacing between them, and thereby providing direct bearing support for the rails over substantially more than fifty percent of their length. Preferably, the slabs have a length in the direction of the track at least three times greater than the spacing between them so that they provide direct bearing support for the rails over at least seventy-five percent of the length thereof. The roadbed material underlying the slabs is uniformly compacted so as to provide a substantially uniform distribution of load bearing capacity over substantially the entire area of each slab. The slabs thus provide maximum support for the rails, and enable rails of given weight to carry greater and faster-moving loads than when conventional wooden crosstie construction is employed.

The rail-supporting slabs used in track construction according to the invention are preferably of reinforced

2

(or prestressed) concrete, and are preferably precast by mass production methods. Metallic rail fastenings, such as bolts to which rail clips and nuts can be applied, are preferably permanently anchored in the slabs. At least one fill-injection opening preferably is formed in the central portion of each slab, for injecting roadbed fill material under the slabs to insure that the load bearing capacity of the roadbed is uniformly distributed over substantially the entire area of the slab.

These and other features of the invention are described below with reference to the accompanying drawing, in which

Fig. 1 is a plan of a railway track constructed in accordance with the invention;

Fig. 2 is a section taken substantially along the line 2—2 of Fig. 1; and

Fig. 3 is a section taken substantially along the line 3—3 of Fig. 1.

The track shown in the drawings comprises a graded roadbed 5 on which rail-supporting slabs 6 are laid. Rails 7 are laid on and secured to these slabs. The slabs 6 are preferably of precast concrete which advantageously is prestressed or is reinforced with steel reinforcing rods 8. The width of the slabs, in the direction of the width of the track, is preferably about equal to the width of conventional wooden crossties (for example about eight feet in the case of a standard gauge track). The thickness of the slabs in a vertical direction may also be about the same as conventional wooden ties (say six to eight inches).

However, the length of the slabs, in the direction of the length of the track, is substantially greater than the corresponding dimension of a wooden crosstie. In the case of the slabs shown in the drawings, their length is approximately equal to the length of two conventional wooden crossties plus the space between them (usually between three and four feet in the case of a standard gauge railway). Slabs of such dimensions are not too large to be handled conveniently by railway construction and maintenance crews, and yet are large enough to provide for achieving substantially the full advantages of the invention. However, the foregoing dimensions for the crosstie slabs are exemplary only, and the invention is not limited thereto.

Each of the slabs 6 carries rail fastenings by which the rails 7 are secured in place. In the slabs shown, the rail fastenings comprise bolts 9 embedded and anchored in the precast slabs, and rail clips 10 which bear against the rail flanges and are secured in place by nuts 11. However, so far as the invention is concerned, there is nothing critical about the form of the rail fastenings provided.

Each of the slabs 6 is formed with one or more fill-injection openings 12 extending vertically therethrough and located in more or less central areas of the slabs (three such openings are shown in the slabs portrayed in the drawing, but their particular number and location can be varied over wide limits, depending on the size of the slabs and the character of the roadbed). These openings provide for injecting fill material to underneath the slabs, and especially to underneath the central portions thereof.

Construction of a railway track in accordance with the invention proceeds as follows: After the roadbed has been leveled to line and grade, the slabs 6 are laid in place. They may be located either in contact with each other, or with small spaces between them as indicated at 13 in the drawings. If any space is provided between the slabs, it is preferably narrow (generally less than a foot), and does not exceed one third the length of the slabs themselves, so that the rails mounted on the slabs are supported over at least seventy-five percent of their length. In any event, the space should be narrow enough so that the beam length of unsupported rail be-

tween the slabs is short and easily able to withstand the bending stresses imposed on it during normal service.

After the rails have been laid on the slabs and fastened in place, the slabs are raised to the correct height by pressure injection of roadbed fill material through the holes 12. The fill is preferably injected at a controlled pressure, so that the roadbed structure underlying the slabs is compacted and the resultant voids caused by said compaction are filled with the fill material. This injection is continued until a substantially uniform distribution of load bearing capacity over substantially the entire area of each slab is obtained. The raising of the slabs to the correct height and the provision for uniform distribution of load-bearing capacity beneath substantially the entire area of each slab cause the slabs to exert a substantially uniform force against the bottom of the overlying rails. The fill material advantageously is cementitious in character, so that when it has set it forms a consolidated mass and provides for stabilizing the bed on which the slabs rest. To retain the fill material in place, the longitudinal sides of the slab are advantageously sealed by tamping with earth, sand, cinders, or the like, and the spaces, if any, between the slabs are advantageously similarly sealed, as indicated at 14. No other ballast is needed, except perhaps in special cases, as where peculiar drainage requirements exist.

Where existing wooden crosstie tracks are to be reconstructed in accordance with the invention, the existing ballast material may be left in place and may be sealed, after the slabs have been laid thereon, by pressure injection of cementitious fill material to prevent the penetration of water below the slabs.

The fill injection holes 12 advantageously are left open, so as to permit later adjustment of the track if uneven roadbed subsidence or other occurrence ever makes it necessary.

The outstanding advantages of our method of railway track construction may be summarized as follows:

The direct support of the rails for much the greater part of their length by concrete tie slabs, instead of support for less than half their length by spaced wooden crossties, provides for increased uniformity in the distribution of dead and live loads over the roadbed area. Therefore, maximum ground surface pressures of the track structure are correspondingly reduced, generally to about 40% of those of conventional wooden crosstie tracks.

The concrete tie slabs cover the ground area under them like a waterproof blanket, whereby penetration of water into the roadbed is minimized and consequent reduction of ground stability by changing moisture content is greatly reduced or may even be made impossible.

The weight of the concrete slabs and their uniform contact with the roadbed as a result of pressure injection of fill materials, are of great importance for obtaining and maintaining superior track stability.

Reduced cost of rails (which may be of reduced weight for given loads and speeds), elimination of ballast, tie plates and spikes, and mass production of the concrete tie slabs, all contribute to track construction costs that are favorable by comparison with other methods.

Termites and other insects destructive to wood are harmless to concrete crosstie slabs. These slabs also are immune to the deteriorating effects of acid or alkaline soil conditions, fungus growths and other destructive influences.

Costs of track maintenance, one of the most severe obstacles to profitable railway operation, are reduced to a mere fraction of present expenditures.

The correctly stabilized track structure with greatly reduced load pressures on the supporting ground, protected against intermittent variations of moisture content, produce the greater possible safety for train operation.

Wherever subsidence of tracks on fills or adverse soil

conditions occurs, the resulting derangement is easily corrected at low cost by pressure injection of additional fill material.

The improved rail support provided by the invention leads to longer lifetime of the rails and equipment, and also decreases the cost of operation.

The greatly increased contact area of the rails on the concrete surface of the supporting tie slabs, and the improved fastening of the rails, minimizes the dangers of rail creeping.

It is quite evident that these advantages all lead to increased safety and economy in railway construction and operation.

It is of course apparent that the design and construction of our concrete tie slabs are subject to variation to meet specific needs. Ribs or stiffeners may be provided where soil conditions or traffic requirements must be considered. Special slabs may be furnished for switches, and for rail and road crossings. Resilient pads of various kinds may be inserted under the rails to subdue train noises, and other accessories can be incorporated in the track structure to meet the most exacting requirements of every type of railway track construction and service.

In the appended claims the term "roadbed" is used to designate the ground upon which the railway is to be laid without application thereto of the usual rock ballast.

We claim:

1. The method of laying a railway track which comprises leveling the roadbed to line and grade, laying railway supporting cross-tie slabs directly on the established grade so that the distance between the respective slabs is less than about one half the width of a slab, securing the rails to the slabs along parallel lines extending substantially normal to the lengthwise direction of the space between the slabs, and pressure-injecting roadbed fill material beneath the slabs to compact the roadbed beneath them and to fill the voids caused by said compaction with the fill material, said pressure-injection being continued until the slabs are raised and exert a substantially uniform force against the bottom of the overlying rails and a substantially uniform distribution of load-bearing capacity beneath the rails under substantially the entire area of each slab has been obtained.

2. The method of laying a railway track as set forth in claim 1 in which the roadbed fill material is cementitious in character and is injected at a controlled pressure through openings extending through said slabs from the top to the bottom.

3. The method of laying a railway track as set forth in claim 2 in which the roadbed fill material is confined substantially to the area underlying the slabs until it has set to form a consolidated, stabilized roadbed mass.

4. The method of laying a railway track as set forth in claim 1 in which the distance between the respective slabs does not exceed more than one third the width of a slab.
